Specification for Design.

Patented June 5, 1917.

Application filed February 21, 1917. Serial No. 150,279. Term of patent 14 years.

To all whom it may concern:

Be it known that I, GEORGE S. HURST, a citizen of the United States, residing at Glastonbury, in the county of Hartford and State of Connecticut, have invented a new, original, and ornamental Design for a Label, of which the following is a specification, reference being had to the accompanying drawings, forming part thereof.

The figure is a view of a label showing my new design.

I claim:

The ornamental design for a label, as shown.

GEORGE S. HURST.
